(57) **CLAIM**

We claim the ornamental design for an information handling system display, as shown and described.

DESCRIPTION

FIG. 1 is a front perspective view of the information handling system display comprising the present invention; FIG. 2 is a front elevation view thereof; FIG. 3 is a rear elevation view thereof; FIG. 4 is a right side view thereof; FIG. 5 is a left side view thereof; FIG. 6 is a top view thereof; FIG. 7 is a bottom view thereof; FIG. 8 is a front perspective detail view thereof as identified in FIG. 1;

FIG. 9 is a front perspective detail view thereof as identified in FIG. 1;

FIG. 10 is a right side detail view thereof as identified in FIG. 4; and,

FIG. 11 is a right side detail view thereof as identified in FIG. 4.

Broken lines shown in the drawings illustrate portions of the information handling system display, and form no part of the claimed design.

Broken lines shown in the drawings illustrating portions of the information handling system form no part of the claimed design. The broken lines indicating portions of the figures shown enlarged form no part of the claimed design.
